UNITED STATES PATENT OFFICE.

ARNOLD MOETTELI, OF OBERWINTERTHUR, SWITZERLAND.

ARRANGEMENT IN COKE CONTAINERS OR THE LIKE.

Application filed January 19, 1922. Serial No. 530,485.

To all whom it may concern:

Be it known that I, ARNOLD MOETTELI, engineer, a citizen of Switzerland, residing at and whose post-office address is Oberwinter-
thur, Romerstrasse 21, Switzerland, have invented certain new and useful Improvements in Arrangements in Coke Containers or the like, of which the following is a specification.

10 The present invention relates to a coke cooling apparatus and the like and has for its object to prevent the formation of bridges occurring in the contents of the container, having the effect of blocking off the container outlet and preventing discharge of the contents.

It has been proposed to prevent formation of such bridges and accumulations within the container by arranging a horizontally positioned member and mounting it for movement up and down the length of the apparatus. An automatic lifting device is associated with this member to raise and lower it through the container and thus 25 break up any accumulations and bridges which tend to form.

It has also been proposed to prevent the formation of these bridges by agitating or shaking a suitable body arranged within the container, the motion of the body being imparted by a suitable driving engine associated with the container.

I have found that bridging over any apparatus of this kind may be effectually prevented by a simple mechanism which does not require for its operation a driving mechanism or other special apparatus. In the practice of my invention I provide two or more pendulum bodies arranged at different points in the container and interconnected in such manner that the motion imparted to any one of the bodies by reason of the movement of the coke in the container is conveyed to the other of the pendulum bodies also. Thus each pendulum body continually moves about more or less and prevents bridging in its immediate vicinity so that by suitably distributing the body throughout the container bridging over of the contents 50 may be effectually prevented. In the pre-

ferred embodiment I arrange the pendulum bodies in vertical relation and suspend them from one another by a series of short chain connections.

An embodiment of the subject matter of 55 the present invention is illustrated in the drawing.

Fig. 1 is a vertical section through the cooling chamber. Fig. 2 is a vertical section through a modified form of cooling 60 chamber.

a represents a receptacle serving for storing and cooling the coke and *b* is the discharging device. Discharging of such receptacles is often rendered difficult on account of so-called bridges formed within such receptacles by the masses of coke, which prevent the top layers of coke from entering the discharge opening. The present invention has for object to overcome this 70 trouble.

In accordance, in said receptacle there are suspended bodies *c*, which are set in motion by the masses of coke flowing to the exit opening, and will thus prevent the formation 75 of bridges and warrant a smooth discharge of the receptacle.

In the mode of construction shown in Fig. 2 the bodies or members *c* are mechanically moved in order to increase their effect, by 80 means of a motor *d* arranged on the outside of said receptacle. Obviously, the said pendulum members may be also moved mechanically in any other suitable manner.

I claim:

1. In a coke cooling apparatus means for preventing bridging of the contents and clogging the container outlet, comprising at least two pendulum bodies arranged at different points in the apparatus and connections between said pendulum bodies for mutually imparting to each of said bodies movements produced by the action of the coke on another of said bodies. 85

2. In a coke cooling apparatus means for preventing bridging of the contents and clogging the container outlet, comprising at least two pendulum bodies arranged at different points in the apparatus, such bodies being linked together in a chain whereby 95 100

movement of any one of said bodies by action of coke will be imparted to the other of said bodies.

3. In a coke cooling apparatus means for preventing bridging of the contents and clogging the container outlet, comprising at least two pendulum bodies arranged at different points in the apparatus, such bodies being linked together to extend longitudinally of the apparatus in the form of a

chain whereby movement of any one of said bodies by action of coke will be imparted to the other of said bodies.

In testimony whereof I have affixed my signature in presence of two witnesses.

ARNOLD MOETTELI.

Witnesses:

F. HEIM,
AUGUST BRIEGG.
